UNITED STATES PATENT OFFICE.

FELIX EDWARD RICE AND WILLIAM ALBERT RUSH, OF NORTHAMPTON, ENGLAND.

INSOLE FOR BOOTS AND SHOES.

1,374,030.

Specification of Letters Patent. Patented Apr. 5, 1921.

Application filed April 1, 1920. Serial No. 370,492.

To all whom it may concern:

Be it known that we, FELIX EDWARD RICE and WILLIAM ALBERT RUSH, subjects of the King of Great Britain and Ireland, of Warko Shoe Works, Artizan Road, Northampton, in the county of Northampton, England, have invented Improvements Relating to Insoles for Boots and Shoes, of which the following is a specification:

10 This invention is an improvement upon insoles for boots and shoes where such insoles have heretofore been composed of three layers.

15 By our present invention, the three layers are reduced to one layer, with the addition of a small wedge of hard leather or other material secured on the top of it, near the waist portion, providing the necessary abutment for the heel pad, such wedge beginning 20 where the seat ends and tapering gradually toward the waist. This results in a sunken seat, and the tapering of the wedge causes it to merge into the surface near the waist, thus producing a continuous smooth area 25 extending from the seat to the toe. A cork or cushion pad is laid upon the sunken seat so as to fill the recess, after the heel has been nailed in place, such pad therefore covering the ends of the nails and thus protecting the foot. The pad may be held by adhesive and it is covered on the top with a thin layer of felt or other soft material which also overlaps the leather wedge. It may be strengthened on the bottom with canvas. 30

35 The overlapping felt can be tapered off to a thin edge at the waist.

The insole, consisting of practically one thickness of leather, is grooved and lipped, in a manner already known, and a strip of 40 canvas or leather is stitched into the upper surface of the insole (by stitches sewn through a channel on the underside) and is stretched over and around the edge of the insole and stuck into the groove formed by 45 the lip and continued so as to completely cover such lip. This strip of canvas or other material effectually protects the edge of the insole and prevents it from turning up in wear.

50 The accompanying drawings illustrate our invention, Figure 1 being a plan of the in-

sole complete, with the heel partly nailed to it. Fig. 2 is a view of the same showing the reverse side or bottom.

Fig. 3 is a central section of Figs. 1 or 2. 55

Fig. 4 is a corresponding section of an auxiliary detail omitted from Figs. 1 to 3.

Figs. 5, 6 and 7 are cross sections (enlarged) of the edge of the insole in three successive stages of progress. 60

Figs. 8 and 9 are perspective views of the heel pad and of the heel end respectively of the insole together with adjacent parts.

The same letters of reference in the various figures denote the same or corresponding 65 parts.

a represents the main body of the insole, which is continuous from end to end of the boot and shoe. *b* is the wedge. *c* is the cork and *f* the felt combined to form a cushion 70 heel pad of known kind.

g denotes the upturned lip of the insole *a* and *h* the edge. *j* is a small groove parallel with the edge upon the bottom of the insole *a*. The protective canvas strip is indicated by *k* and the manner of attaching is shown by Figs. 5, 6 and 7, the leather *a* being first channeled as at *l*, before the canvas strip *k* is stitched by thread *m*, so as to occupy the groove *j* (see Fig. 6). The 75 strip is afterward folded around the edge *h* and the lip *g*, to which it is stuck, and is stuck also into the large rectangular groove or rabbet formed by the junction of *g* and *h* (see Fig. 7). 85

The canvas covered lip *g* is used for stitching the upper to, as is commonly known.

We claim:

An insole including a sole portion and a heel portion, a wedge shaped member forming a part of the insole and secured to the upper surface thereof, said wedge shaped member having one edge thereof forming an abutment, a cushioning member adapted to be assembled with the above portions 90 after the attachment of the heel and to engage the abutment, and means carried by the cushioning member and adapted to overlap the wedge member for cushioning the upper surface of the wedge member. 95

FELIX EDWARD RICE.

WILLIAM ALBERT RUSH.
